UNITED STATES PATENT OFFICE.

DANIEL M. FRYE, JR., OF PHILADELPHIA, PENNSYLVANIA, ASSIGNOR, BY MESNE ASSIGNMENTS, TO UNITED SHOE MACHINERY CORPORATION, OF PATERSON, NEW JERSEY, A CORPORATION OF NEW JERSEY.

MEASURING DEVICE.

1,348,861.

Specification of Letters Patent. Patented Aug. 10, 1920.

Application filed November 17, 1916. Serial No. 131,940.

To all whom it may concern:

Be it known that I, DANIEL M. FRYE, Jr., a citizen of the United States, residing at Philadelphia, in the county of Philadelphia and State of Pennsylvania, have invented certain Improvements in Measuring Devices, of which the following description, in connection with the accompanying drawings, is a specification, like reference characters 10 act on the drawings indicating like parts in the several figures.

This invention relates to measuring devices for use in the making of boots and shoes and particularly to an implement for measuring a shoe to which the heel has not been attached to ascertain the height of heel required for the shoe and for measuring the height of heel to ascertain whether the heel is of the height required for the shoe which 20 has been previously measured.

It is important that a shoe made on a given last be provided with a heel of exactly the right height to cause the forepart to contact with a plane surface along a predetermined line extending across the ball of the shoe. When the shoe is provided with a heel of the proper height, the forepart contacts with the surface walked on along a well defined line extending across the ball 30 of the foot and the shoe is then said to "tread right."

Heretofore the selection of the heel for a given last has been made more or less by guess and in a haphazard manner, and in consequence many shoes are put upon the market which do not tread right, the line of contact at the forepart being too far forward or too far to the rear, and the tread faces of the heels of which do not bear 40 squarely upon the surface walked on. Such shoes are not only inferior in appearance, but the wearing quality of the shoe is impaired.

An object of this invention is to provide 45 a convenient implement for measuring an unheeled shoe, when placed with the tread face of the ball resting on a plane surface, to ascertain the height of heel required by that shoe in order to make it tread right, 50 that is, to bring the line of contact of the tread surface of the forepart at the proper location longitudinally of the shoe.

A further object of the invention is to provide an implement for measuring unat-

tached heels to facilitate the selection of 55 the proper heel for a previously measured shoe.

As herein shown, the implement consists in a plate having a foot or flange adapted to be held in contact with the flat surface 60 against which the forepart of the shoe to be measured is rested, the plate having an edge inclined to the plane upon which the foot or flange rests and provided with teeth along the inclined edge in the form of steps 65 ascending by equal gradations from the flange or foot. The teeth or steps are adapted to sustain the rear portion of the shoe at varying elevations by contact with the rear portion of the heel seat. Preferably and as shown, the steps are arranged at vertical distances from the surface against which the foot rests, differing by $\frac{1}{8}$ of an inch whereby the vertical location of the rear portion of the shoe is indicated in that 75 unit, which is the unit usually employed in measuring the height of heels.

The implement further comprises a straight edge and a flange at right angles to that edge adapted to contact with the 80 top lift of an unattached heel, the straight edge being provided with a scale to indicate directly the height of the heel in the same units adopted for measuring the proper elevation for the rear portion of the shoe. 85

Figure 1 shows the measuring implement in use to ascertain the height of heel required by a given shoe;

Fig. 2 shows the implement in use for determining the height of a heel; and 90

Fig. 3 is a perspective view of the implement.

The implement consists of a plate 2, preferably of metal, having a flange 4 at one end perpendicular to the plate and arranged in an angle (shown as approximately 45°) with one edge of the plate. This inclined edge is formed with teeth or steps, the rise of each step over the preceding one being $\frac{1}{8}$ of an inch, the steps preferably being numbered consecutively from the one nearest the flange and the height of the first step being measured from the outer face of the flange. This is because the height of the first step must include the thickness of 95 the flange and the height of that step must be measured from the surface on which the outer face of the flange rests. When the im-

lement is held in the position shown in Fig. 1 with the flange 4 resting against the plane horizontal surface, the stepped edge is inclined at an angle to the horizontal and one edge 6 of each step is horizontal, the other edge 8 being substantially vertical.

A shoe to be measured for a heel is placed with the tread face of its forepart in contact with the surface upon which the flange 10 4 rests, and the shoe is rocked on its forepart until the line of contact of the forepart with the surface is correct for the given last. The shoe and the stepped edge of the implement are then brought in contact and the number opposite the horizontal edge 6 of the step which engages the rear edge of the heel seat is noted. In the case shown in Fig. 1 the number is 24. This shows at once that a 24-8 heel (that is, a heel twenty-four-eighths of an inch high) is required to make the given shoe tread right.

To ascertain whether a given heel is suitable for the shoe measured, as described, a flange 10 on another edge of the implement is brought in contact with the tread face of the heel. The flange 10 is arranged perpendicular to an edge 12 of the implement which is provided with a scale 14 beginning from the inner face of the flange 10, the unit being $\frac{1}{8}$ of an inch, as in the case of the stepped scale. Since the heel tread rests on the inner face of the flange 10 the zero point of the scale 14 must be at the inner face of this flange. After the flange 10 is engaged 30 with the tread face of the heel the implement is moved along until the scale 14 is adjacent to the rear portion of the heel seat engaging face of the heel, as in Fig. 2. The height of the heel is then read from the scale, and in the instance shown, the scale indicates that the heel is a 24-8 heel and suitable to be attached to the shoe shown as being measured in Fig. 1.

Having thus described my invention, 45 what I claim as new and desire to secure by United States Letters Patent is:—

1. A device of the class described comprising a base adapted to rest on a flat surface, a graduated portion arranged to extend upwardly in an inclined direction from the base and marked to afford a direct reading of the number of units of heel height measurement of the heel required for a heelless shoe when the shoe is positioned with its forepart in proper tread relation to said flat surface, a second base, and another graduated portion arranged to extend perpendicularly to said base and marked to afford direct reading of the number of units 55 of heel height measurement of a shoe heel.

2. A device of the class described comprising a base adapted to rest on a flat surface, a portion arranged to extend upwardly in an inclined direction from the base and provided with notches spaced to indicate 60

the number of units of heel height measurement of the heel required for a heelless shoe being measured, said notches being adapted to support the heel end of the shoe when its forepart is in proper tread relation to said flat surface, a second base, and another graduated portion arranged to extend perpendicularly to said base and marked to afford direct reading of the number of units of heel height measurement of a shoe heel. 70

3. An article of manufacture comprising a plate having two graduated edges and two flanged ends, one of the flanges being inclined to one edge and the other flange being perpendicular to the other edge, the 80 gradations on the edge to which the first mentioned flange is inclined being spaced by heel measuring units from the outer face of said flange.

4. An article of manufacture comprising a plate having two graduated edges and two flanged ends, one of the flanges being inclined to one edge and the other flange being perpendicular to the other edge, the 85 gradations on the edge to which the other flange is perpendicular being spaced by heel measuring units from the inner face of said other flange.

5. An article of manufacture comprising an elongated plate having one straight edge 95 and one notched edge, flanges on each end of the plate perpendicular to the plane of the plate, one flange being perpendicular also to the straight edge, and the other end being inclined to the notched edge. 100

6. An article of manufacture comprising an elongated plate having one straight edge and one notched edge, a flange on each end of the plate perpendicular to the plane of the plate, one flange being perpendicular also to the straight edge, and the other flange being inclined to the notched edge, said straight edge having equal gradations each 105 equal to the difference in perpendicular distance of adjacent notches from the flange inclined to the notched edge. 110

7. An article of manufacture comprising an elongated plate having one straight edge and one notched edge, and flanges located one at each end of the plate perpendicular to the plane of the plate, one flange being perpendicular also to the straight edge, and the other flange being inclined to the notched edge, said straight edge having 115 gradations numbered consecutively from the inner face of the flange perpendicular to said edge, the notches being numbered consecutively from the outer face of the inclined flange. 120

8. A device of the class described comprising a base adapted to rest on a flat surface, and a portion arranged to extend upwardly in an inclined direction from the base and provided with notches spaced to indicate the number of units of heel height 125

measurement of the heel required for a heelless shoe being measured, said notches being adapted to support the heel end of the shoe when its forepart is in proper tread relation to said flat surface, and said portion being provided with graduations for measuring the height of a heel for the measured shoe in units corresponding to the spacing of the notches.

9. An article of manufacture comprising 10 a plate having two graduated edges and two flanged ends, the plane of one of the flanges being inclined to one edge and the plane of the other flange being perpendicular to the other edge.

15 In testimony whereof I have signed my name to this specification.

DANIEL M. FRYE, JR.
